UNITED STATES PATENT OFFICE.

WILLIAM H. BAKER, OF CENTRAL FALLS, RHODE ISLAND, AND FREDERIC E. KIP, OF MONTCLAIR, NEW JERSEY.

PNEUMATIC SHUTTLE-MOTION FOR LOOMS.

SPECIFICATION forming part of Letters Patent No. 674,157, dated May 14, 1901.

Application filed March 23, 1900. Serial No. 9,842. (No model.)

To all whom it may concern:

Be it known that we, WILLIAM H. BAKER, residing at Central Falls, Providence county, Rhode Island, and FREDERIC E. KIP, residing at Montclair, Essex county, New Jersey, citizens of the United States, have invented certain new and useful Improvements in Pneumatic Shuttle-Motions for Looms, of which the following is a specification.

- 10 This invention relates to the class of looms wherein a compressed aeriform fluid, as compressed air, is employed for picking or driving the shuttle. In this class of looms the shuttle is usually made to fit snugly into the shuttle-box, somewhat in the manner of a piston in a cylinder, and when the shuttle is expelled the compressed fluid following it is apt to break or disarrange the warps. Hence it is very important in order to avoid such injury 15 to the warps to effect in some manner a deflection of the compressed fluid or the main portion thereof laterally, upward, or downward before it can escape from the receiving end of the shuttle-box.
- 20 The object of the present invention is to provide means for so deflecting the compressed fluid, and said invention is illustrated in the accompanying drawings.

In the drawings, Figure 1 is a front elevation of a part of a loom provided with our improvements; and Figs. 2 and 3 are enlarged detail views of the shuttle-box, Fig. 2 being a sectional plan and Fig. 3 a sectional front view thereof. Fig. 4 is a modification of the 25 device for deflecting the fluid.

Referring primarily to Figs. 1, 2, and 3, *a* represents the loom-frame; *b*, the breast-beam forming a part thereof; *c*, the lay; *d*, the reed; *e*, the shuttle-box mounted thereon; *f*, the swing-rail; *g*, the lay-swords; *h*, the crank-shaft for operating the lay, and *i* a shaft driven therefrom through gears *j*.

k is a pipe to lead compressed air (from any source) to a charge-holder *l*. *m* is a valve 45 controlling the entry of air to said holder.

n is a pipe leading air from the holder.

o is a pipe swiveled to the pipe *n* at *p* in line with the swing-rail. Said pipe *o* is connected at its upper end with the shuttle-box 50 and vibrates with the lay. A valve *q* controls the flow of air from the holder *l*, said

valve and the valve *m* being spring-valves which close automatically. On the shaft *i* is a cam *r*, which opens the valves *m* and *q* alternately to admit, first, a charge of compressed air to the holder *l*, and, second, to admit this charge to the shuttle-box for picking or driving the shuttle *s*.

All of the above features are shown in our Patent No. 659,950, of October 16, 1900, and are not in themselves claimed herein, but are used for purposes of illustration.

Referring particularly to Figs. 2 and 3, two swing-valves *t* are hinged in the shuttle-box, Fig. 2, and are held open so as to lie out of the path of the shuttle by light springs *u*. The valves are fixed on their hinge-pins *v* and have fixed on said pins outside of the box two intermeshing segment-gears *w*, which compel the valves to move together. The ends of the springs *u* are connected to arms on said hinge-pins or on the gears. Preferably the shuttle-box *e* will have two box-like recesses *x* for the open valves *t* to fold into. Air-conduits *yy* are situated at opposite sides 75 of the shuttle-box and connected at one end *y'* with the interior of the box at some point between the valves *t* and the position occupied by the shuttle when the latter is in the box and at the other end with the respective 80 recesses *x* behind the respective open valves. The recesses *x* are open to the atmosphere through apertures *z*.

The operation is simple. When compressed air is admitted behind the shuttle, the latter is driven out toward the right in the drawings. As its tail passes and uncovers the inlets *y'* to the conduits *y* the compressed air enters the conduits and passing through them impinges upon the valves *t*, so as to close them behind the shuttle as the latter leaves the box. The valves close together in the V-like position indicated in dotted lines in Fig. 2, their meeting edges being beveled to produce a snug fit and prevent the escape of any considerable amount of air between them. The air escapes from the shuttle-box somewhat gradually through the apertures *z* in a lateral direction, and, if desired, it may be led to any point from the apertures *z* where its discharge will produce no injurious effect.

It is not material to our invention whether

the valves *t* be placed above and below or at the sides of the box. They will remain closed until the pressure of air in the box is low enough to be overcome by the springs *u*, when 5 the latter will open them, so that the shuttle may enter from the opposite side of the loom without contact with them.

Fig. 4 shows means for deflecting laterally the charge of air that has expelled the shuttle. 10 In this construction the shuttle-box is connected at its front part through conduit 1 with an exhaust-cylinder 2, mounted on the loom-frame and having in it a piston 3, connected by a rod 4 with a lever 5, fulcrumed 15 on the loom-frame. This lever carries a roller 6, which bears on a cam 7, rotatable with a shaft 8 of the loom. The cam 7 is so set that at the moment the picked or driven shuttle uncovers the port of the conduit 1 the cam 20 will quickly draw down the piston 3, thus producing a vacuum in the relatively large chamber in the cylinder 2, produced by the displacement, and the compressed air will thus be deflected to the cylinder. The size of 25 the cylinder and the stroke of the piston may be varied to suit the circumstances. The piston may be returned to the position seen in Fig. 4 by a spring 9 or other known means. This construction of Fig. 4 is best adapted 30 to looms where the shuttle-box is fixed at the picking-point and does not vibrate with the lay.

Being the first, so far as we are aware, to provide a loom wherein the shuttle or weft-carrier is picked by an aeriform fluid under 35 tension with means for deflecting the picking charge of fluid or the major portion thereof after it has done its work, we do not limit ourselves to any specific means for doing this. 40 We have shown two devices whereby it may be effected; but we should consider any means by which the tension of the charge of fluid in the box behind the shuttle is materially reduced by deflection as soon as it has done its 45 work to be within the scope of our invention.

Our invention may be applied to looms wherein the shuttle is picked by an aeriform fluid from a shuttle-box forming one of a series of shuttle-cells in a magazine—such, for 50 example, as the magazine illustrated in our Patent No. 659,950, of October 16, 1900—where it forms a part of an automatic weft-supply mechanism, or in a double-shuttle loom of the same character, such as that described in 55 our pending application, Serial No. 739,874, filed December 11, 1899.

The purpose of this invention is to provide an automatic means operating synchronously with or controlled by the outgoing shuttle to 60 prevent the picking charge or the major por-

tion thereof from expanding from the entrance of the shuttle-box in the direction of the axis of the box and to relieve the tension by expansion in another direction where it can do no injury.

65

Obviously this invention relates to the class of pneumatic devices for driving a shuttle where the compressed charge impinges directly on the shuttle, as it is only in this class that the expanding charge follows the shuttle into the web or the shed of the loom. Where a piston is interposed between the shuttle and the charge, this difficulty is not experienced.

In our Patent No. 659,950, before mentioned, lateral apertures are shown in the shuttle-director to allow for some lateral expansion of the charge; but no device or mechanism is shown for preventing expansion of the charge or the major portion thereof in 80 the direction of movement of the outgoing shuttle.

Obviously it would be possible to dispense with one of the by-pass conduits *y*, as the valves are compelled to move together, but 85 the two conduits are preferred.

Having thus described our invention, we claim—

1. A loom having means for picking or driving the shuttle or weft-carrier to and fro with 90 a compressed aeriform fluid, and mechanism for deflecting the picking charge, or the major part thereof, after it shall have done its work, said mechanism comprising a pair of valves in the shuttle-box, means for holding 95 said valves normally open, and means for admitting a part of the picking charge behind said valves to close them, said means being controlled by the outgoing reciprocating shuttle.

2. In a loom, the combination with the 100 shuttle-box, means for admitting thereto a charge of compressed air for picking or driving the reciprocating shuttle, and the shuttle, of means connected with the shuttle-box and controlled by the outgoing shuttle for 105 deflecting the picking charge, or the major portion thereof, after it shall have done its work, said means comprising the valves *t*, their springs *u*, said valves being held open, normally, by the springs, and adapted to 110 close the box, the outlets *z* in the box, and the conduits *y*, substantially as set forth.

In witness whereof we have hereunto signed our names, this 12th day of March, 1900, in the presence of two subscribing witnesses.

WILLIAM H. BAKER.
FREDERIC E. KIP.
